MOISTUREPROOF PAPER CONTAINER WITH CLOSURE

Filed Nov. 5, 1931

UNITED STATES PATENT OFFICE

GUNTHER MEYER-JAGENBERG, OF DUSSELDORF, GERMANY

MOISTUREPROOF PAPER CONTAINER WITH CLOSURE

Application filed November 5, 1931, Serial No. 573,188, and in Germany November 7, 1930.

This invention relates to improvements in paper containers and the method of making same.

Paper containers of round or square shape in cross section are old in the art, each specific and particular form having peculiar disadvantages, either when in use or in the adaptability of the containers when transporting same.

10 The object of the present invention is to provide a container combining in one the two shapes required and at the same time provide integral closure flaps adapted to be brought together and clipped to seal the 15 container.

A further object of the invention is to provide a container of conical form at the bottom and square at the top to not only afford means for convenient stacking of the 20 containers for transporting purposes, but also to provide strength to resist the strain of the contents at the point where it is most needed.

The invention also comprehends improvements in the method of making the containers, the cylindrical body portion being formed on a conical mandrel, the upper part being then squared on a second mandrel, encased in a surrounding form, and 25 thereafter the flaps or folds are formed.

The invention also comprehends improvements in the details of construction and arrangement of parts as will be hereinafter described and particularly pointed out in 30 the claims.

In the accompanying drawing:

Fig. 1 is a perspective view of a container constructed in accordance with my invention, the flaps or closure being open.

40 Fig. 2 is a similar view showing the flaps closed and sealed.

Fig. 3 is a detail perspective view illustrating the folds of the flaps at one side of the container.

45 Fig. 4 is a detail section on the line 4—4 of Fig. 2.

Fig. 5 is a plan view, with the sealing element omitted.

50 Fig. 6 is a horizontal section on the line 6—6 of Fig. 2.

a indicates the main conical body portion of the container, cylindrical in cross section and merging at its upper end in a square form in cross section, as shown at *a*¹. The bottom edge of the cylindrical portion *a* is turned inwardly to embrace the depending edge *b* of a disk *c*, the latter forming a bottom for the container. The contacting edges of the body portion *a* and the disk *c* are glued to rigidly bind the parts together. 55

The squared form *a*¹ at the upper end of the container is creased entirely around the container, as indicated at *a*². Spaced above the crease line *a*² and extending around the square portion of the container is a second 60 crease line *a*³. The four corners of the squared upper end are creased, as shown at *a*⁴ for convenience in folding. Two opposite sides of the squared portion of the container are formed with diagonal creases *a*⁵—*a*⁶ extending from the juncture of the creases *a*⁴ and *a*² to the center of the crease *a*³ and from the latter points there are vertical creases *a*⁷ extending to the upper edge 65 of the container. 70

In the manufacture of the container, the paper is wrapped around a conical mandrel and the longitudinal edges glued, thus forming a conical tube. The material may have 75 previously been impregnated with waterproofing material, or it may be treated, for instance, with paraffin, after the tube is formed. The lower edge of the tube is bent to engage the edge of the disk and glued. 80

A second mandrel, round at its bottom and square at its upper end, is now inserted in the upper end of the tube to square the material slightly below where the crease *a*² will be formed. At the same time, the conical tube is inserted in a surrounding form, 85 square at its upper end to correspond with the shape of the second mentioned mandrel, thus confining the major portion of the conical tube, and at the same time shaping the upper portion square. The upper portion 90 of the tube having been properly shaped with its walls free of the mandrel, from a point above the first crease *a*², the walls are bent inwardly on the top of the mandrel and the creases *a*², *a*³, *a*⁴, *a*⁵ and *a*⁶ are formed. 95 100

Thus the flaps or closure elements are provided. The flaps are opened, the second mandrel and the surrounding form are removed.

5 The container, when completed, includes a conical body portion and a square upper end, with creases so located as to facilitate convenient folding for closing the upper end of the container. For instance, assuming the 10 container has been filled, say up to about the line of crease a^2 , and it is desired to close the upper end, the triangular portions a^7 formed by the creases a^2 and a^5 on opposite sides of the square upper end are folded inwardly, while the triangular portions a^8 fold outwardly and rest on the portions a^7 . In making these folds, the rectangular portions a^9 fold inwardly toward each other, and due to the creases a^8 , the portions a^{10} 15 fold together side by side, with the rectangular end portions a^{11} . When the flaps or folds are closed as described and as shown in the drawing, a U-shaped clip f is slipped over the upper edges of the portions or flaps 20 a^8 and a^{10} , thus sealing the container.

Obviously, a container constructed as described possesses strength and durability and is convenient in packing for transportation.

25 10 What I claim is:

1. A paper container including a conical body portion round at the bottom and gradually merging into square form at the top, the four sides of the square upper end being creased to form folding closure flaps.

2. A container comprising a lower body portion cylindrical in cross section and a square upper end, the sides forming the square upper end of the container having horizontal, vertical and angular creases to 30 form folding flaps for closing the container.

3. A container comprising a lower body portion cylindrical in cross section and a square upper end, the sides forming the square upper end of the container having spaced apart horizontal creases, two opposite sides of said sides having upwardly inclined creases joining at the upper of the horizontal creases, said sides further having vertical creases extending from the upper horizontal crease to the edge of the container, whereby the upper portions may be folded to form a closure, with two opposite sides lying vertically side by side, and a U-shaped 35 sealing element fitted over the two folded vertical portions.

4. A container of paper or like material having a body portion of conical outline vertically and of round contour transversely, the upper end of the body portion being rectangular in transverse section, and including movable portions for interfitting to provide a closure for the container.

5. A container of flexible material having 40 a conical body and a rectangular upper end,

a portion of the walls of the upper end being interfolded to form a closure for the container.

6. A container of flexible material having a body conical in vertical outline and round in transverse outline, a closure for the bottom of the body, the upper end of the wall of the body being of square outline in transverse section, a portion of the upper end of the body wall forming relatively movable parts capable of association to provide a closure for the container.

7. A container of flexible material having a body conical in vertical outline and round in transverse outline, a closure for the bottom of the body, the upper end of the wall of the body being of square outline in transverse section, the upper portion of the walls of the body forming the square outline being interfolded to form a closure for the body.

In testimony whereof I affix my signature.

GUNTHER MEYER-JAGENBERG.
